(57) **CLAIM**

I claim the ornamental design for a hair shaver with adjustment tool, as shown and described.

DESCRIPTION

FIG. 1 is a perspective view of the hair shaver with adjustment tool in accordance with the principles of the present disclosure;

FIG. 2 is a first-side elevational view of the hair shaver with adjustment tool in accordance with the principles of the present disclosure;

FIG. 3 is a second-side elevational view of the hair shaver with adjustment tool in accordance with the principles of the present disclosure;

FIG. 4 is a top plan view of the hair shaver with adjustment tool in accordance with the principles of the present disclosure;

FIG. 5 is a bottom plan view of the hair shaver with adjustment tool in accordance with the principles of the present disclosure;

FIG. 6 is a front axial view of the hair shaver with adjustment tool in accordance with the principles of the present disclosure; and,

FIG. 7 is a left-side elevational view of the hair shaver with adjustment tool, the opposite right-side elevational view being the mirror image, in accordance with the principles of the present disclosure.

The broken lines illustrate portions of the hair shaver with adjustment tool, and form no part of the claimed design.
